UNITED STATES PATENT OFFICE

ROBERT PRINDLE MIDDLEKAUFF, OF LA GRANGE, ILLINOIS, ASSIGNOR TO WESTERN ELECTRIC COMPANY, INCORPORATED, OF NEW YORK, N. Y., A CORPORATION OF NEW YORK

COMPOSITE RELAY STUD

Original application filed August 30, 1927, Serial No. 216,465. Divided and this application filed July 11, 1928. Serial No. 291,917.

This invention relates to composite articles and more particularly to composite insulating studs for electro-magnetic relays and the like.

The present invention is a division of my copending application, Serial No. 216,465, filed August 30, 1927.

In certain types of apparatus and particularly in various classes of electrical apparatus, such as electro-magnetic devices or relays, extensively employed in telephone exchange systems, a plurality of superimposed circuit closing contact springs are operated by a common armature. These springs are arranged in parallelism and in order to actuate certain of them, insulated stud members or pins are used which are carried by the movable armature of the relay. It has heretofore been the practice in certain instances to use insulating studs comprising a pair of insulator sleeves which are pressed over opposite extremities of a metallic core member having a central positioning collar, and obviously in the production of such studs a considerable number of individual forming and assembling operations must be performed to complete the assembly of each stud.

The primary objects of this invention are the provision of a rigid and durable composite article which comprises few and simple parts and which may be economically and expeditiously manufactured.

In accordance with the general features of the invention there is provided in one embodiment thereof a composite relay stud comprising a metallic core member having a sleeve of insulating material extruded thereon and machined to the desired shape or contour, the core member being provided with a plurality of surface indentations whereby the insulating sleeve is firmly secured thereto.

These and other objects and advantages of the invention will be more apparent from the following detailed description when considered in connection with the accompanying drawings, wherein

Fig. 1 discloses a fragmentary sectional view of a knurling mechanism which is representative of one specific type of apparatus

which may be employed to form the indentations upon the surface of the metallic core;

Fig. 2 is an enlarged fragmentary detailed view of a knurled core member produced by the mechanism shown in Fig. 1;

Fig. 3 is a fragmentary sectional view of an extrusion mechanism which may be employed for extruding a covering of insulating material upon the knurled core member shown in Fig. 2;

Fig. 4 is a fragmentary perspective view of a knurled core having a coating of insulating material applied thereto;

Fig. 5 is a fragmentary detailed view of the composite cylindrical stock of the insulating material and core member disclosed in Fig. 4;

Fig. 6 is a view similar to Fig. 5 with an end portion of the composite cylindrical stock turned down to form a relay stud;

Fig. 7 is a view similar to Fig. 6 showing a completely formed relay stud at one end of the composite cylindrical stock;

Fig. 8 discloses an insulating stud which has been completed and severed from the cylindrical stock;

Fig. 9 is a detailed perspective view of the completed relay stud disclosed in Fig. 8, and

Fig. 10 is a fragmentary detailed elevational view of a relay of the type employed in telephone circuit which is equipped with a unitary stud of the type disclosed in Figs. 8 and 9, a portion of the relay parts being broken away to more clearly disclose the position of the stud.

Referring now to the drawings wherein like numerals have been employed to designate similar parts throughout the various figures, it will be observed that Fig. 1 discloses a knurling mechanism denoted generally by the numeral 20 which comprises a pair of oppositely disposed knurling cutters 21 rotatably mounted within companion blocks 22. Surrounding the cutters 21 and blocks 22 is a casing or housing 24 provided with apertured thimble members 25 which serve to guide a core member 26 which is passed or drawn between the cutters 21. When the core member 26 is drawn between these cutters, oppo-

site surface portions of the core are formed with a plurality of indentations or depressions 28 and said core is then in condition to be passed through an extruding mechanism 5 denoted generally by the numeral 29 (Fig. 3).

This extruding mechanism 29 is similar to the apparatus disclosed in the copending application of Ray Charles Kivley, Serial No. 112,599, filed May 29, 1926, which comprises

- 10 a jacketed body portion 30 which houses a conveying screw 32 driven in a suitable manner. Insulating material 33 is fed downwardly through the action of the screw 32 into association with an extrusion head 34 through 15 which the core 26 is passed. The extruding mechanism 29 applies a very uniform insulating coating 36 of desired thickness which may subsequently be hardened by any convenient heat treating or vulcanization process. Surrounding the core 26 with the uniform covering or coating of insulating material 36 presents a composite cylindrical stock or rod which is designated by the numeral 37.

This composite cylindrical stock 37 which 25 comprises the knurled core 26 and the insulating coating 36 applied thereto may now be turned down in a lathe automatic screw machine or other suitable devices (not shown) so as to present an insulating stud

30 having a desired surface, shape or contour. One extremity of the composite stock shown in Fig. 5 may be turned to form a reduced portion or shank 38 (Fig. 6) and the outer extremity of this shank 38 is slightly beveled at the point 39. The stock 37 may be further formed by cutting a groove 41 (Fig. 7) of desired depth which serves to present a second reduced portion or shank 42 which is oppositely disposed from the shank 38.

40 By making another cut, the reduced portions 38 and 42 together with a shoulder portion 43 therebetween may be completely severed from the remaining portion of the stock 37. These portions 38, 42 and 43 together with the reinforcing core 26 present a completed stud which is denoted generally by the numeral 45.

The particular type of insulating stud 45 disclosed in Figs. 8 and 9 is peculiarly adapted for use in connection with certain types of electro-magnetic relays 46 (Fig. 10) which are extensively used in telephone exchange systems for opening and closing electrical circuits. This type of relay includes a group 50 of contact springs 47 which are associated with a relay winding 49. An armature 50 associated with the winding 49 supports the stud 45 in vertical position and is adapted to be swung downwardly from the position shown in Fig. 10 when the relay is sufficiently energized. The downward swinging of the armature 50 causes the beveled extremity of the shank 38 to force one of the adjacent contact springs 47 downwardly so as to effect the contact thereof with a spring

positioned immediately therebeneath. The shoulder portion 43 may also engage a contact spring of the relay upon the downward movement of the armature 50. In order to more fully understand the operating characteristics of the relay 46 reference may be made to the co-pending application of Earl Victor Johnson, Serial No. 183,440, filed April 13, 1927, wherein this type of relay is described in detail. The relay 46 is merely shown as one example of the practical application of the improved insulating stud and therefore a detailed description of the relay is not believed to be necessary for a complete and thorough understanding of the invention.

From the foregoing it will be understood that a composite part or stud embodying the features of the invention is unitary in structure, comprises few and simple parts, and may be economically and expeditiously manufactured. It will also be apparent that by extruding the insulating covering upon a core provided with knurled surfaces as described, the core and covering are firmly secured to each other and shifting of the core with respect to the covering is positively precluded.

Although the invention has herein been described in connection with a particular type of composite member or stud used with particular types of electro-magnetic relays, it is to be understood that the invention is capable of many other applications and should be limited only by the scope of the appended claims.

What is claimed is:

1. A composite stud member for electro-magnetic relays comprising a core having a surface indentation, and a cylindrical covering of insulating material co-extensive with the core and filling the indentation, a portion of said covering material being reduced in diameter.

2. A composite insulating stud member for electro-magnetic relays comprising a core member having a plurality of pairs of separated diametrically opposed transverse surface indentations, and a unitary body of insulating material varying in diameter throughout its length and interlocking with the indentations.

3. A composite insulating stud member for electro-magnetic relays comprising a metallic core having a plurality of surface indentations, and a cylindrical covering of insulating material extruding and vulcanized upon the core and filling the indentations, said cylindrical covering having end portions of different diameters, and a central portion of greater diameter than the diameters of the end portions.

4. A composite insulating member for spring type relays comprising a core member and a unitary covering of insulating ma-

terial firmly secured thereto, said covering tapered to one end of the core and having a shoulder for operative engagement with a relay spring.

5 In witness whereof, I hereunto subscribe my name this 29th day of June A. D., 1928.

ROBERT PRINDLE MIDDLEKAUFF.
